UNITED STATES PATENT OFFICE

KARL E. JENSEN, OF CHICAGO, ILLINOIS, ASSIGNOR TO INDUSTRIAL GLOVES CORPORATION, OF CHICAGO, ILLINOIS, A CORPORATION OF DELAWARE

GLOVE

Application filed November 16, 1928. Serial No. 319,780.

The invention relates generally to gloves and more particularly to reinforcing means for increasing the wearing quality of gloves of the type especially adapted for use in the handling of rough, sharp, and heavy articles such as metal castings or the like.

It has been found in practice that gloves used for heavy work, especially those used in connection with the handling of castings, 10 wear out rapidly throughout the palm portion of the glove, the side portion adjacent the index finger stall and the lower portions of each of the finger stalls. It has also been found that these gloves tend to pull apart or 15 break at the seams of the crotches between adjacent finger stalls.

It is an object of the present invention to provide a new and improved reinforcing member for strengthening the gloves throughout these parts.

A more specific object of the invention resides in the provision of a single reinforcing piece which overlies and is secured to the palm of the glove and which extends outwardly to 25 protect the lower portions of the finger stalls, as well as the crotches therebetween, which extending portion is unsecured to the glove in order to retain the inherent flexibility of the glove construction.

30 Other objects and advantages will appear in the following description and from the accompanying drawings in which:

Figure 1 is a front view of the glove with a portion of the reinforcing member turned 35 to an abnormal position to show the preferred form of construction.

Fig. 2 is a side view of the glove as it normally appears looking toward the right in Fig. 2.

40 While the invention is susceptible of various modifications and alternative constructions, I have shown in the drawings, and will herein describe in detail the preferred embodiment, but it is to be understood that I do 45 not thereby intend to limit the invention to the specific form disclosed, but intend to cover all modifications and alternative constructions falling within the spirit and scope of the invention as expressed in the appended 50 claim.

An important feature of the invention resides in the provision of a reinforcing member which may be constructed in a single piece and readily incorporated in the glove during the manufacture thereof and which, 55 due to the manner in which the piece is applied, as will be presently set forth, provides a loose flap portion extending and maintained in protective relation with those portions of the glove subject to the greatest 60 amount of bending.

More particularly described, the preferred embodiment of the invention is shown in the drawings as being applied to a commercially well-known type of glove indicated generally at 5 which is of any desired construction and may include a suitable gauntlet 6. A thumb stall 7 of the butterfly or other well-known type is provided on the palm, and, 65 since the present invention relates only generally thereto, need not be more fully described.

The preferred form of reinforcing member 10, in this embodiment, comprises a piece of leather or other suitable flexible wear resisting material which is previously cut in the form of a blank having a palm covering portion 11 cut away to fit about the thumb stall 7 and a side flap 12 (Fig. 2). The side flap 12 is arranged when the reinforcing 75 member is applied to the glove to extend around the index finger side of the glove and the palm covering portion is substantially longer than the palm, in the longitudinal direction of the glove, to provide a flap portion 13.

Metallic staples 15 or wire stitching may be employed to secure the reinforcing member firmly and permanently to the palm of the glove. At the same time the side flap 12 90 is secured around the side of the glove. The outwardly extending flap portion 13, however, remains unsecured, and the last line of staples or stitching, which secures the reinforcement to the glove, indicated generally 95 by the dotted line A—A, in Fig. 1, stops short of the crotches on the palm side thereof. Thus the flap 13 loosely overlies the base portion of the finger stalls and the crotches and permits a slight relative movement there- 100

between when the glove is flexed across these points. Since the side flap 12 is curled about the side of the index finger stall the flap 13 is also curved through this portion, which serves as a stiffening means for maintaining the flap 13 in its proper position overlying the base portion of the finger stalls. This normally maintained position of the flap is indicated in dotted lines in Fig. 1.

As shown, metallic staples or stitching is preferably disposed about the entire surface of the reinforcing body and the glove and the flap 13 may be also provided with these staples which act to increase the wearing quality and durability of the glove.

From the foregoing description of the preferred embodiment, it will be apparent that a glove has been provided which is reinforced across those portions subject to the greatest wear and which due to the slight relative movement permitted by the loose flap overlying the finger stalls and crotches does not in the least impair the flexibility of the glove. Furthermore, the novel provision of a rolled portion at one side of the flap operates to maintain the flap in its normal protecting position.

I claim as my invention:

A glove including a palm and finger elements having, in combination, a reinforcing member comprising a palm covering part secured to the palm, a flap extending from the palm covering part loosely to overlie the crotches and the base portions of the finger elements and unsecured thereto, and a side portion extending from the palm covering part and flap secured about the index finger side of the palm to form a curl at one side of said reinforcing member tending to maintain said flap in its normal position overlying said finger elements.

In testimony whereof, I have hereunto affixed my signature.

KARL E. JENSEN.
